UNITED STATES PATENT OFFICE.

JAMES LAWRENCE, OF NEW YORK, N. Y., ASSIGNOR TO STANLEY G. RANGER, OF NEW YORK, N. Y.

ELECTRIC HEATER.

1,177,254.

Specification of Letters Patent. Patented Mar. 28, 1916.

Application filed November 19, 1915. Serial No. 62,313.

To all whom it may concern:

Be it known that I, JAMES LAWRENCE, a subject of the King of Great Britain, and a resident of New York city, in the county 5 and State of New York, have invented certain new and useful Improvements in Electric Heaters, of which the following is a specification.

My invention relates to electric heaters, 10 and particularly to that type of heaters which includes heating units comprising resistance members carried by a supporting body.

One of the most practical methods of deriving heat from electrical energy is by passing the electric current through resistance coils. So far as the transference of electrical energy to heat is concerned, this method has proved highly efficient. But heretofore the 15 devices designed for utilizing the heat generated from the resistance coils has been very inefficient. It is well known that the rate of heat radiation from a body increases in greater proportion than the intensity of 20 the temperature of that body, and therefore in my device it is my intention that the heating elements shall be kept at the highest possible intensity of temperature, even though the elements may thereby be consumed; and in order to overcome the inconvenience due to the burning out of the elements, I intend that the elements shall be 25 readily replaceable. A well-known fault present in the electric heating units of this 30 day is that a great amount of heat generated by the heating elements is absorbed by the member which supports the heating element. In my device, therefore, the support for the heating element is made with a minimum 35 cubical content, so that while it sufficiently supports the radiant element, it does not absorb and store up a great amount of heat and thereby reduce the available energy, or hold unavailable heat long after 40 the material which it is desired to heat has had sufficient heat applied to it.

One object of my invention is to provide 45 a heating unit including a plate for supporting resistance elements and formed to insure a maximum of direct radiation of heat at a maximum intensity from the resistance element to the body to be heated, the plate having the minimum cubical content consistent with practical considerations.

Another object is to provide simple, 55 economical and practical means for securing an electric heating element to a supporting body to form a heating unit.

Another object is to provide an electric heating unit which is complete and includes 60 electrodes for the introduction of electric current and which is adapted to be removably operatively positioned in a receiving member.

Another object is to provide a heating unit 65 comprising a heating element supporting plate having means for draining away from the heating element material spilled over the unit.

Another object is to provide a heating unit 70 comprising a heating element and a plate for supporting the element and provided with means to secure a circulation of heat generated by the element.

Another object is to provide a receiving 75 member for an electrical heating unit which is durable and resistant to the effect of temperature variations.

Another object is to provide a receiving member for an electrical heating unit, the 80 heating unit having electrodes for the introduction of electricity and the receiving member having spring contacts for accommodating the electrodes of a heating unit 85 to supply electricity to the unit, said receiving member also being provided with means for protecting the contacts from the heat generated by the unit and from material spilled over the unit.

Another object is to provide a heating 90 unit and a receiving member therefor, the unit and member being formed to provide means for preventing heat from being conducted from the unit to the receiving member.

Another object is to provide a support for 95 an electric heating unit receiving member whereby a complete electric heater is provided wherein the heating units are readily interchangeable.

Other and further objects and advantages 100 of my invention will be disclosed in the following description taken in connection with the accompanying drawings forming a part of this specification, and will be pointed out in the claims.

105 In the drawings, in which like reference characters indicate similar parts, Figure 1 is a top view of an electric heater embody-

ing my invention; Fig. 2 is a partial cross-section on the line $x-x$ of the device shown in Fig. 1; Figs. 3, 4 and 5 are detail sectional views of devices for anchoring the heating element to a supporting plate; Figs. 6 and 7 are, respectively, partial plan views of the modification shown in Figs. 4 and 5; and Figs. 8 and 9 are plan views of modifications of heating unit receivers.

10. The electric heater which is illustrated by the drawings and described in this specification is one embodiment of my invention and is described for purposes of interpretation thereof. The top plate 1 of the heater, together with the legs 2 attached thereto, comprises a support for the heating unit receiver 3, and the heating unit receiver carries the heating unit plate 4 on which there are mounted heating elements 5. The 15 top 1 of the heater has a circular opening therein, and to the top are secured brackets 6 upon which rest the circular receiving member 3, which is slightly smaller than the hole in the top 1, thereby leaving an opening 8 between the top of the support and the receiver 3, so that air may circulate through the opening to prevent the conduction of heat from the receiver to the support. The upper surface of the top 1 is 20 shown by Fig. 2 to be slightly above the upper surface of the receiver 3, so that heavy articles placed upon the heater may be supported by the strong supporting member rather than by the heating member 4 which 25 is of refractory material. The difference in the level of the upper surfaces of the receiver and the top 1 also permits receptacles which are warped to be placed into close contact with the heating plate 4. The heating plate 4, as shown by Figs. 8 and 9, is 30 a circular member having openings 9 and a cross bar 10. The openings may be large as shown in Fig. 8, in which case the rim is provided with slots 11 to relieve strains 35 arising in the circular portion by reason of variation in the temperature of the receiving member. The openings 9 may be small as shown in Fig. 9, and the receiving member is made in three parts, 3^a, 3^b, and 3^c, 40 and variations in temperature will not cause its destruction. Within the upper surface of the receiver there is a circular opening. Adjacent the wall of this opening there is 45 formed in the receiving member a supporting ledge 12, and upon this ledge the heating unit 4 is supported so that its upper surface is practically flush with the upper surface of the receiver, but it is to be understood that I do not confine myself to the 50 detailed arrangement described.

Either upon the ledge or upon the lower face of the plate 4 of the heating element projections 13 are formed which elevate the plate 4 above the ledge. The plate 4 is made 55 smaller than the opening in the receiving

member and the circulation of air between the receiver and the plate is provided for to prevent conduction of heat from the plate 4 to the receiving member. In the upper surface of the plate 4 there are concentric 70 spiral grooves 14. These grooves, in the embodiment described, have a flat bottom and perpendicular sides extending to a point intermediate the top and the bottom of the groove. Upward from this point the sides 75 of the groove diverge substantially uniformly. In this groove there is positioned the heating element 5, which comprise helical coils of suitable resistance wire of such material and dimensions that it will be heated immediately to incandescence without a great initial rush of current when the current is turned on, and will be kept at a destructive temperature thereafter. The plate 4 is of refractory material and so designed 80 that they are readily replaceable because the heating element is operated at a destructive temperature. It is designed to have the minimum cubical content possible without substantial loss of strength, so that heat of 85 the heating element will not be taken from the article to be heated when current is first turned on, or stored up to be wasted after the current is turned off. The opening at the top of the grooves is entirely unobstructed and it will be seen from the shape of the grooves that the radiation from the heating element will be the freest possible to obtain, and that absorption of heat by the 90 sides of the groove will be almost negligible. 100

The ends of the heating element near the edges of the plate are passed through openings in the plate, as are also the ends of the elements at the center. To the back of the plate at the edges and at the center, as 105 clearly seen in Fig. 2, there are secured electrodes 15 which extend down through holes 16 in the cross bar 10 of the receiving member 3. Secured to the lower face of the receiving member, by bolts 18, there are contact supporting bars 17. On each of these 110 contact supporting bars there is mounted a spring clip 19 which, as shown in Fig. 2, accommodates one of the electrodes 15 when the heating unit is dropped into the opening 115 in the receiving member. Binding posts 20 on each bar 17 are adapted to conduct current to the spring clips 19. The lower ends of the holes 16 are enlarged, and flanges 20 surround these enlarged portions and form 120 therewith chambers 31 which surround the spring clips 19 and thoroughly protect them from the heat of the heating elements and from any material which may pass through the drain holes 32 a plurality of which extend through the plate 4 from the bottom 125 of the groove therein.

In the upper surface of the receiving member there are formed grooves 21 so that the heating unit plate 4 may be grasped by 130

the fingers to remove it. In the upper face of the heating unit plate there are provided radial grooves 22 which intersect the grooves in which the heating elements are positioned. This is to permit circulation of heat across the face of the heating element when only one of the two concentric spirals of the heating elements is radiant.

It is old to retain the heating element in its groove by forming projections extending from the top edge of the walls of the groove out over the heating element. These projections I have done away with, in order that all of the heat may radiate directly to the article to be heated, and I have shown several methods of anchoring the heating element within its groove. In Fig. 3 I have shown a preferred form of heating element anchor. The heating element is formed with long loops of wire 24 which pass through openings 25 through the plate in the bottom of the groove. The long loop 24 is then spread out into the wide loop 26 and subsequently flattened into the knot of wire 27 shown at the right of Fig. 3. By anchoring the heating unit in this way a negligible portion of the heating unit is covered by the plate and at the same time a very simple and efficient anchoring means is provided. In Fig. 4 I have shown an anchoring means which consists in a loop of wire passed through one hole in the plate over one loop of the heating element and back through to another hole in the plate and knotted to prevent loosening. In Fig. 5 I have shown a loop of wire passing through a single hole in the plate and inclosing a loop of the heating element and being knotted to prevent its being pulled through the plate by any strain on the heating element.

While it is old to have a heating element of the type which I employ positioned in a straight groove, the top opening of which is unobstructed, it will be seen that I have devised a heating unit which includes a plate having a curved groove the top opening of which is unobstructed and the heating element, which is positioned in the groove, is held from straightening out and positioning itself above the top of the groove by anchors which hold it against the bottom of the groove.

While I have described with considerable detail a single embodiment of my invention, it is to be understood that modifications, variations and adaptations of my device or elements thereof which occur to those skilled in the art, are considered to be within the scope of my invention which I desire to be defined only by the hereunto appended claims.

Having thus described my invention, what I claim as new and desire to secure by Letters Patent, is:

1. As an article of manufacture, a heating

unit comprising a plate having a continuous uninterrupted groove in one face thereof and openings extending from the bottom of said groove through said plate, and a coiled heating element positioned in and extending substantially throughout said groove, said element having uncoiled portions comprising loops extending through said openings to anchor said element to said plate at intervals throughout the extent of said element.

2. As an article of manufacture, a heating unit comprising a plate having a continuous groove in one face thereof and recesses in the other face thereof and openings extending from the bottom of said groove through said plate and into said recesses, and a heating element positioned in said groove, said element having loops extending through said openings and being shaped to coöperate with the opposite face of said plate within said recesses to anchor said element to said plate at intervals throughout the extent of said element.

3. In a device of the class described, a heating unit having electrodes for the introduction of electricity thereto, a receiving member for said unit, spring supply contact members for coöperating with said electrodes to deliver current thereto, and means carried by said receiving member to protect said contacts from the heat generated by said unit.

4. In a device of the class described, a heating unit comprising a body member of insulating material and a heating-unit-supporting receiving member having a recess into which said body member fits and comprising a ring and a cross-bar, said ring being split to avoid strains due to temperature variation.

5. In a device of the class described, a heating unit comprising a body member of insulating material and a heating-unit-supporting receiving member of refractory material comprising separated segments of a ring and a member joining said segments, the inner surface of said ring being shouldered to permit said unit to rest within said receiving member.

6. In a device of the class described, a heating unit comprising a plate having a plurality of grooves in one face thereof, and heating elements, respectively positioned in said grooves, said plate having additional grooves having a cross-section substantially equal to that of said first named grooves; respectively connecting portions of said first-named grooves, whereby heat may circulate uniformly when a body rests on said plate.

7. In a device of the class described, a heating unit comprising a plate having concentric spiral grooves in one face thereof, and heating elements extending throughout said grooves, said plate having radial grooves having a cross-section substantially

equal to that of said first-named grooves intersecting said spiral grooves.

8. In a device of the class described, a heating unit comprising a plate portion of insulating material, a receiving member therefor comprising a ring having a shoulder portion formed on its inner surface to support said plate at its edges, one of said portions being provided with projections for separating said portions to permit air circulation.

9. In an electric stove, the combination of a removable and replaceable heating unit support, a heating unit comprising a heating element of such construction and resistance as to be raised to incandescence substantially immediately upon the passage of a current of the voltage for which it is designed, said heating unit being so positioned upon its support as to permit of the ready removal of such heating unit and its replacement by another similar heating unit, and electrical conducting surfaces on the heating unit support and said unit so arranged as to contact with one another and close electrical connection at such points upon the mere placing of the unit in its place in the support, whereby electrical heating units may be used capable of being brought to a high degree of heat at once upon the passage of current and

that when burned out such heating units may be readily removed and replaced.

10. In a device of the class described, a heating unit having electrodes for supplying current thereto, a supporting member for said unit and having perforations through which said electrodes extend, and spring supply contacts with which said electrodes coöperate after passing through said supporting member.

11. In a device of the class described, a heating unit having electrodes for supplying current thereto, a cross-bar passing beneath said unit and having recesses in its lower face, and openings through said bar into said recesses, spring supply contacts in said recesses, said electrodes being adapted to extend through said openings to coöperate with said contacts.

12. In an electric heater, a stand comprising a top plate and supporting means therefor, said plate having an opening therein, a receiving member of insulating material supported by said stand within said opening and spaced from the edge thereof, and an electric heating unit carried by said receiving member and removable therefrom.

In testimony whereof, I have signed my name to this specification.

JAMES LAWRENCE.
